OIL TREATING MEANS

Charley Lowery, Oklahoma City, Okla., assignor
of twenty per cent to Charles Ray Woodcock,
Oklahoma City, Okla.

Application March 28, 1936, Serial No. 71,500

5 Claims. (Cl. 196—3)

This invention relates to the treatment of oil and more particularly to an improved method and means whereby water and gas is removed from oil.

An object of this invention is to provide an improved method of separating the oil from water which is contained in the oil and, at the same time, separating the gas from the oil so that the gas will not affect the treatment of the oil, the gas being later returned to the oil after the oil has been treated.

Another object of this invention is to provide a treating means for separating oil from water or other undesirable elements, such as sand or the like, and at the same time heating the oil so as to facilitate the separation of the oil from water or other undesirable elements.

A further object of this invention is to provide an improved treating means of this kind whereby oil may be treated in a continuous process so as to remove the water or other ingredients therefrom, the water being broken up by the heating medium so that any oil contained in globules of water will be separated.

A still further object of this invention is to provide an exceedingly simple treating means of this character which can be mounted in a tank of suitable size so that any desired quantity of oil may be treated and so that the separated water may be drawn off during the treatment of the oil.

The above and various other objects and advantages of the invention will in part be described in, and in part be understood from the following detail description of the present preferred embodiment, the same being illustrated in the accompanying drawing, wherein:—

Figure 1 is a vertical section partly in detail of an oil treating means constructed according to an embodiment of this invention.

Figure 2 is a fragmentary sectional view taken on the line 2—2 of Figure 1.

Figure 3 is an enlarged fragmentary sectional view of one of the oil treating nozzles embodied in this invention.

Referring to the drawing wherein like symbols designate corresponding parts throughout the several views, the numeral 10 designates generally a heating tank or member provided with a head 11, and a boss 13 through which an intake oil discharging pipe 12 extends. A cap or gland member 14 engages the boss or nipple 13 so as to seal the pipe 12 in the head 11. A T or pipe connection 15 is secured to the upper end of the intake pipe 12 and a laterally extending oil supply pipe 16 is connected at one end to a source

of oil supply and at the other end to one side of the T 15.

The pipe 12 extends substantially to the bottom 17 of the tank 10 and the lower end of the pipe 12 is perforated or cut out, as at 18, and a plate 19 is secured to the lower end of the pipe 12 and contacts with the inner side of the bottom 17. Preferably, there are a plurality of teeth 20 on the sides of the cut out portion 18 and the bottom plate 19 also has a plurality of standing teeth 21. Preferably, this plate 19 is relatively larger in diameter or size than the diameter of the pipe 12 at the lower end thereof.

The tank 10 is adapted to contain water to substantially the line indicated by the numeral 22 and oil to substantially the level indicated by the line 23 which is substantially in line with an outlet pipe 24 connected to the side wall of the tank 10 and also connected to a storage reservoir or the like.

A sight glass 25 is secured to the tank 10 at a point substantially with the center of the sight glass in line with the top of the water indicated by the line 22 and this water level may be maintained by means of a water outlet connection 26 at substantially the bottom of the tank 10.

A reducing connection 27 is connected to the top of the T 15 and a branch 28 is connected to a T or suitable pipe connection 29 secured to the top of the reducing connection 27. This branch 28 extends horizontally and then vertically and downwardly, as at 30, and terminates in the outlet pipe 24 so that the gas in the oil entering the connection 15 will rise in the connections 27 and 29 and then pass horizontally and downwardly 35 and enter the cleaned or treated oil as this oil passes out of the tank 10 and into the storage reservoir. A valve 31 is in the pipe 28 and a by-pass 32 carrying a pressure regulator 33 bridges the valve 31. This by-pass 32 has valves 34 and 35 on opposite sides of the regulator or vent 33. A pressure gauge 36 is in the pipe 28 between the by-pass connection 32 and the T-connection 29.

A chemical container 37 is connected to the T 29 by means of a pipe 38 and a valve 39 is interposed in this pipe 38 so that when desired the chemical in the container 37 may be discharged downwardly into the pipe 12.

A plurality of oil circulating pipes 40 are disposed within the tank 10 with their lower ends carrying plates 41 which engage the bottom 17 and these circulating members 40 are secured to the pipe 12 by means of radial braces 42. The upper ends of the circulating members 40 are

open and project slightly above the water line 22 so that the heavy oil above the water line 22 will be drawn downwardly and discharged through the jet means comprising the V-shaped openings 43 at the lower ends of the pipes 40. A plurality of confronting teeth 44 are carried by the pipes 40 in the V-shaped portions 43 and the bottom plates 41 are also provided with upwardly extending teeth 45 which are similar to the upwardly extending teeth 21 carried by the bottom plates 19. The heavy oil above the water line 22 is drawn downwardly through the pipes 40 by means of steam jet members 46 which are disposed inside the pipes 40 below the open tops 15 thereof and these jet members 46 are connected as by radial branches 47 to a steam pipe 48 which extends downwardly through the pipe 12 and terminates at a point spaced upwardly from the bottom plate 19 thereof. The pipe 48 is connected by means of a pipe 49 to a source of steam supply and this pipe 49 connects with the pipe 48 through the wall of the pipe 12 exteriorly of the tank 10.

The oil which is known as "cut oil" is pumped 25 through the pipe 16 and then down through the pipe 12. The gas in the oil will rise in the dome-like connection 27 and then pass through the pipe 28 and the pressure regulator 33, the valves 34 and 35 being open at this time and the valve 30 31 being closed. Steam will be discharged downwardly through the pipe 48 from the steam supply pipe 49 and the lower end of the pipe 48 is formed as a nozzle so that this steam will commingle with the downwardly moving oil and heat 35 the oil as it moves downwardly. The oil will be discharged through the openings 18 in the pipe 12 and the teeth 20 in the sides of the openings 18 will break up the globules or bubbles of water so that oil contained in these globules or bubbles 40 will be freed and permitted to rise upwardly as free oil through the water in the bottom of the tank 10. At the same time, that the oil enters the tank 10 through the pipe 12, the oil above 45 the water line 22 will be drawn downwardly through the circulating members 40 and then reheated by steam discharged from the steam jets 46. The steam will not only reheat this oil but will also serve as a suction means to draw the heavier oil lying just above the water line 22 50 downwardly through the circulating members 40 and then force this oil out through the openings 43. The oil passing through the openings 43 will pass between the teeth 44 on the sides of the openings 43 and will also pass through the teeth 45 carried by the bottom plates 41. The light and completely treated oil will rise in the tank 10 55 to the line indicated at 23 and then flow out through the pipe 24 into a suitable storage tank or may be disposed of in any other convenient manner.

The quantity of water indicated by the line 22 may be maintained in the tank 10 by means of the outlet connection 26 which may have a suitable valve interposed therein so that as the water rises in the tank 10 the outlet 26 may be drained to the proper point indicated by the sight glass 25 in order that no water will be disposed above the tops of the oil circulating members 40.

I claim:—

1. A means for treating oil containing water and gas comprising a tank, an intake pipe extending interiorly of the tank and terminating at substantially the bottom thereof, a bottom plate carried by the intake pipe, said intake pipe having openings adjacent the bottom, a plurality of

teeth carried by the intake pipe about the edges of the openings, a plurality of upwardly extending teeth carried by the bottom plate, means for discharging steam inside the intake pipe at a point adjacent the lower end thereof, an outlet pipe connected to the tank adjacent the top thereof, and a pipe connected to the intake pipe and to the outlet pipe and disposed exteriorly of the tank whereby to by-pass the gas rising in the intake pipe.

2. A means for treating oil comprising a tank, an intake pipe extending downwardly into the tank and terminating at substantially the bottom thereof, a bottom plate secured to the lower end of the intake pipe, said intake pipe having opposed teeth in the openings thereof, upwardly extending teeth carried by the bottom plate, an outlet pipe connected to the tank at a point adjacent the top thereof, a gas by-pass pipe connected to the intake pipe and to the outlet pipe exteriorly of the tank, pressure regulating means carried by said by-pass pipe, a plurality of vertically disposed oil circulating members disposed in the tank about said intake pipe and provided with open opposite end portions, the tops of the oil circulating members being normally disposed above the normal level of water in the tank, means for discharging steam into the intake pipe at a point adjacent the lower end thereof, and means connected to said steam discharging means and disposed in the circulating members for drawing oil in the tank downwardly through the circulating members.

3. A means for treating oil comprising a tank having a body of water disposed therein, an oil discharging pipe extending vertically into the tank and terminating at a point adjacent the bottom thereof, said discharge pipe having openings adjacent the lower end thereof, a bottom plate secured across the lower end of the discharge pipe and having a diameter substantially greater than the diameter of the discharge pipe, teeth secured to the discharge pipe in the openings thereof, upwardly extending teeth carried by the plates, an outlet pipe connected to the tank adjacent the upper end thereof, a plurality of vertically disposed oil circulating members disposed in the tank and provided with open upper end portions, said circulating members having openings in the lower end portions thereof, teeth carried by the circulating members in the openings thereof, bottom plates secured to the lower ends of the circulating members, upwardly extending teeth carried by said plates exteriorly of the circulating members, means for discharging a heating agent into the discharge pipe at a point adjacent the lower end thereof, and means connected to said latter means for discharging the heating agent into the circulating members in a manner whereby to draw oil disposed within the tank downwardly through the circulating members.

4. A treating means for oil comprising a tank, an intake pipe extending downwardly into the tank and terminating at the bottom thereof, said intake pipe having openings therethrough adjacent the lower end thereof, teeth carried by the intake pipe in the openings thereof, a plurality of oil circulating members disposed in the tank about the intake pipe, means for securing the oil circulating members in parallel relation to the intake pipe, means for discharging steam into the intake pipe at a point adjacent the lower end thereof, means for discharging steam in a downward direction into the circulating members, said

circulating members having openings in the lower ends thereof, teeth carried by the circulating members in the openings thereof, an outlet pipe connected to the tank adjacent the top thereof, 5 a gas by-pass connection connected to the intake pipe and to the outlet pipe exteriorly of the tank, pressure regulating means carried by said by-pass pipe, and means connected to the intake pipe for discharging chemical into the oil passing into the intake pipe.

10 5. An oil treating means comprising a tank

having an outlet disposed above the bottom thereof, an inlet pipe extending into said tank and terminating at a point adjacent the bottom thereof, a plurality of tubular oil circulating members in the tank about said inlet pipe, said circulating members having open upper and lower ends, means supporting said circulating members about said inlet pipe, and means for discharging a heating medium in a downward direction within said circulating members. 10
